US0D1063260S

(12) **United States Design Patent** (10) **Patent No.:** **US D1,063,260 S**
(45) **Date of Patent:** **** Feb. 18, 2025**

(54) **BARK CONTROL COLLAR**

(71) Applicant: **Shenzhen kersonic Intelligent Technology Co., Ltd.**, Guangdong (CN)

(72) Inventor: **Yongkai Zhou**, Guangdong (CN)

(73) Assignee: **Shenzhen kersonic Intelligent Technology Co., Ltd.**, Shenzhen (CN)

(**) Term: **15 Years**

(21) Appl. No.: **29/863,552**

(22) Filed: **Dec. 20, 2022**

(51) LOC (15) Cl. **30-99**

(52) U.S. Cl.

USPC **D30/199**

(58) **Field of Classification Search**

USPC D10/78, 80, 104.1; D13/168, 154; D14/137, 217, 218; D30/144, 151, 152, D30/160, 199
